Primary Examiner — Jeffrey D Asch(74) *Attorney, Agent, or Firm* — Haynes and Boone, LLP(57) **CLAIM**

The ornamental design for a handheld device, as shown and described.

DESCRIPTION

FIG. 1 is a front, left, and top perspective view of a handheld device embodying the new design;

FIG. 2 is a back, right, and bottom perspective view thereof;

FIG. 3 is a front elevational view thereof;

FIG. 4 is a back elevational view thereof;

FIG. 5 is a left side view thereof;

FIG. 6 is a right side view thereof;

FIG. 7 is a top plan view thereof; and,

FIG. 8 is a bottom plan view thereof.

The broken lines in the figures are shown for the purpose of illustrating portions of the handheld device and/or environmental matter and form no part of the claimed design.

1 Claim, 7 Drawing Sheets(56)
